Primary Examiner — T Chase Nelson*Assistant Examiner* — Laura H Yu(74) Attorney, Agent, or Firm — Fross Zelnick Lehrman & Zissu, P.C.; Charles T. J. Weigell, Esq.(57) CLAIM

The ornamental design for footwear, as shown and described.

DESCRIPTION

FIG. 1 is a front perspective view of footwear showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the footwear, showing my new design in an alternative embodiment;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the drawings illustrate stitching and form no part of the claimed design.

The cross-hatching in the drawings shows a textured cross-hatched surface.
